UNITED STATES PATENT OFFICE

GEORGE D. SHAEFFER, OF BUCYRUS, OHIO, ASSIGNOR TO W. A. RIDDELL COMPANY, OF BUCYRUS, OHIO, A CORPORATION OF OHIO

ROAD GRADER AND THE LIKE

Application filed September 30, 1929. Serial No. 396,107.

This invention as indicated relates to road graders and the like, and has more particular reference to improvements in the front axle construction of such graders, and has for an object to provide a means whereby the oscillation of such front axle in the transverse plane with respect to the main body of the grader may be arrested when such rigidity is desired to render the grader more suitable to particular types of work which it may be called upon to perform. Other objects and advantages will appear as the description proceeds.

In spreading loose stone or other like material over an uneven road surface, it is highly desirable that the finished surface be as smooth as possible and free from objectionable waves. If the implement carrying frame is permitted to oscillate as the vertical pressure on the grader blade varies in its passage over the rough, unfinished road surface, such oscillation will cause a wavy finished surface. If, however, such implement carrying frame is locked against oscillation, this rigidity will materially assist in steady-
ing the grader blade with a correspondingly smoother finished surface resulting.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of the various mechanical forms in which the principle of the invention may be used.

In said annexed drawings:

Fig. 1 is in part a side elevation and in part a sectional view of a road grader embodying the principle of my invention; Fig. 2 is a fragmentary front elevation of the grader shown in Fig. 1; Fig. 3 is a side view of that portion of the grader shown in Fig. 2; Fig. 4 is a fragmentary part section and part elevation of the stabilizer in locked position; Fig. 5 is a view similar to Fig. 4 showing the stabilizer in the non-locking position.

Referring more specifically to the drawings and more especially to Fig. 1, the grader here

shown consists of a main implement-carrying frame 1 supported at the forward end thereof by wheels 2 and supported near the rear end thereof by a tractor unit 3. It is to be understood that the improvements disclosed in this invention may be used in connection with graders other than the tractor-propelled type shown in this figure. An adjustable implement supporting arm 4 extends rearwardly from the front axle and is supported intermediately of the ends of the carrying frame by means of adjustable arms 5. Depending from this adjustable arm 4 is an implement 6 which is shown in the present figure to be the common type of grader blade. The implement-carrying frame 1 is oscillatorily mounted at its forward end on the front axle 7 more specifically shown in Figs. 2 and 3. Attached to the front axle 7 by means of supports 8 and 9, forming a part of the forwardly-extending yoke 10, is a vertically-extending yoke or arch 11 lying in a substantially vertical plane. Said yoke or arch member 11 passes through a guiding element 12 which is rigidly attached to the forward end of the implement-carrying frame by means of bolts 13 passing through apertures 13' formed therefor in the element 12. Said member 12 has an upwardly-extending lug 14 rearwardly attached thereto to maintain said yoke member 11 in proper relation to the forward end of the implement-carrying frame. The guiding element 12 has forwardly extending therefrom a projection 15 adapted to slidably secure the pin 16 in the apertures 14' and 15'. The securing pin 16 has co-axially mounted therewith a spring 17 which bears against a washer 18 and maintains the pin 16 in engagement with an aperture 17' formed therefor centrally of the upper portion of the yoke member 11. The engaging pin 16 has a tapered end 19 to assist in the engagement of the pin 16 with the yoke member 11. The securing pin 16 has a forward end 20 extending from the guiding element 15 which has formed therein an aperture 21' to receive a pivot pin 21 pivotally connecting the securing pin 16 to a cam element 22. The element 15 has a lug 27 projecting forwardly therefrom, which lies between the two side ele-

ments of the cam member 22 and along with the securing pin 16 keeps such cam element in operative alignment with the element 15.

- The cam element 22 has a bearing surface 23 adapted to engage the forward surface 24 of the guiding element 15 and has projecting therefrom an arm 24 with an aperture 25 formed near one end thereof, to which is secured the controlling lever 26. As illustrated in Fig. 4, when the controlling lever 26 has been moved to the forward position here illustrated, the spring 17 moves the securing pin 16 into operable engagement with the aperture 17' of the yoke member 11. In this position the implement-carrying frame 1 is secured against oscillation with respect to the front axle 7. As illustrated in Fig. 5, when the controlling lever 26 has been pulled back to the position here indicated, the cam element 22 has been rotated about the pivot pin 21 so that the surface 28 of the cam element 22 rests against the forward surface 24 of the element 15. The surface 28 of the cam element 22 is so formed that when the cam is in the position illustrated in Fig. 5 the spring 17 will hold the cam in this position without any locking means being necessary for the controlling lever 26. When the cam occupies the position illustrated in Fig. 5, the end 19 of the pin 16 has been withdrawn from the aperture 17' of the yoke member 11, thereby permitting the oscillation of the implement frame with respect to the front axle when the conditions of operation under which the implement is employed do not necessarily require rigidity of the implement frame. When the locking pin 16 rigidly secures the implement frame 1 against oscillation the grader is especially adaptable to use in spreading loose stone or other like material over a road surface. The rigidity of the implement frame with respect to the front axle as the vertical pressure on the grader blade varies in its passage over the uneven road surface materially assists in the uniformity with which the grader blade operates, thereby producing a correspondingly smoother finish to the spread stone or other like material.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a road grader and the like, the combination with an implement-carrying frame, of an axle oscillatorily mounted on said frame and provided with supporting wheels, and a vertically disposed yoke attached to said axle and adapted to releasably engage said frame to restrain undesired transverse oscillation of the body frame.

2. In a road grader and the like, the combination with an implement-carrying frame, of an axle oscillatorily mounted on said frame and provided with supporting wheels, a vertically disposed yoke attached to said axle, and a securing element attached to said frame adapted to engage said yoke to restrain undesired transverse oscillation of the body frame.

3. In a road grader and the like, the combination with an implement-carrying frame, of an axle oscillatorily mounted on said frame, a vertically disposed yoke attached to said axle, a guiding means for said yoke attached to said frame and a reciprocal member in said guiding means adapted to coact with said yoke to restrain undesired transverse oscillation of the body frame.

4. In a road grader and the like, the combination with an implement-carrying frame, of an axle oscillatorily mounted on said frame, a vertically disposed yoke attached to said axle, a guiding means for said yoke, and securing means adapted to coact with said yoke and frame to restrain undesired transverse oscillation of the body frame.

5. In a road grader and the like, the combination with an implement-carrying frame, of an axle oscillatorily mounted on said frame, a vertically disposed yoke attached to said axle, a means for guiding said yoke, reciprocal means for fixedly securing said yoke to said frame, and cam means for actuating said reciprocal means.

Signed by me this 27 day of September, 1929.

GEORGE D. SHAEFFER.
